UNITED STATES PATENT OFFICE.

WALTER N. McCLELLAN, OF BROOKLYN, NEW YORK, ASSIGNOR OF TWENTY PER CENT. TO GLADSTONE M. HINTSON, OF BROOKLYN, NEW YORK.

CAR-DOOR-ACTUATING MECHANISM.

1,369,681.

Specification of Letters Patent. Patented Feb. 22, 1921.

Application filed May 18, 1920. Serial No. 382,433.

To all whom it may concern:

Be it known that I, WALTER N. McCLELLAN, a citizen of the United States, and resident of the city of New York, borough of Brooklyn, in the county of Kings and State of New York, have invented a new and Improved Car-Door-Actuating Mechanism, of which the following is a full, clear, and exact description.

10 This invention relates to a car door operating mechanism and has particular reference to a means for controlling the entry and exit of passengers to and from the same, said invention being in the nature of an improvement over a similar device set forth in Letters Patent of the United States granted to me March 9th, 1920, bearing Patent No. 1333430.

20 The invention primarily contemplates a means for controlling the entry and exit of passengers to and from a car, said means being operable from a common control point preferably located within convenient reach of the motorman.

25 An important feature of the invention resides in the provision of the safety devices for reducing the possibility of accidents to passengers to a minimum.

Another object in view is to provide an 30 efficient fare collecting means which controls the exit passages of the car.

A still further object in view resides in the provision of the safety doors and the means 35 automatically operable thereby for bridging the gap between the alighting station platform and the car.

A further object in view is to provide an 40 automatic signaling means which notifies the motorman that the door passages are clear for the closing of the safety doors.

Another feature of the invention is the provision of a safety means carried by the door which functions to fend off passengers attempting to board or leave the car while 45 the safety doors are closing.

With the above recited and other objects in view, some of which will clearly appear hereafter, reference is made to the following detailed description, claims and accompanying drawings which form a part of this application, and in which:

Figure 1 is a horizontal sectional view through a railway car constructed in accordance with the invention.

55 Fig. 2 is a longitudinal sectional view

therethrough taken approximately on the line 2—2 of Fig. 1.

Fig. 3 is an enlarged fragmentary longitudinal vertical sectional view taken approximately on the line 3—3 of Fig. 4. 60

Fig. 4 is a fragmentary vertical transverse sectional view taken on the line 4—4 of Fig. 3.

Fig. 5 is a similar view illustrating the 65 opened position of the steps for bridging the space between the station platform and the car.

Fig. 6 is an enlarged detailed fragmentary 70 sectional and diagrammatic view of the mechanism for controlling the exit from the car.

Fig. 7 is a fragmentary horizontal sectional view taken approximately on the line 7—7 of Fig. 6.

Fig. 8 is a diagrammatic view of the 75 controlled signaling means.

Fig. 9 is a horizontal sectional view 80 through one of the doors illustrating the fenders arranged thereon.

Fig. 10 is a detailed sectional view of the 85 safety covering which may be used in connection with the fenders.

Referring to the drawings by characters of reference, 10 designates a car provided on its opposite sides with entrance passages 11 and exit passages 12. The opposite ends of the car are provided with the cabs 13 for the operator thereof and in which is adapted to be arranged the common controlling means for all of the safety 90 doors.

Sliding safety doors 14 are arranged adjacent each entrance and exit passage and the same are opened and closed by means of a lever 15 which is pivoted as at 16. The 95 levers 15 are preferably actuated by compressed air which is admitted to the cylinder 17 behind the piston head 18 from the supply pipe 19 when the valve 20 is actuated to admit air to the supply pipe from the 100 reservoir 21 which may be charged in any suitable well known manner. A piston rod 22 is connected by a link 23 to the lever 15 and a coiled compression spring 24 is disposed between the piston head 18 and the 105 cylinder head 25 to normally exert a force for effecting the closing of the door 14. In order to provide means for locking the door in its closed or open positions, a latch 26 is pivoted adjacent thereto as at 27, the nose 110

28 of which is adapted to respectively engage the rear end of the door or the notch 29 provided in its forward end. The latch is designed to be released by a compressed 5 air actuated means which includes the cylinder 30 in which is arranged the piston 31 connected by the piston rod 32 to the latch arm 33, air being admitted to the cylinder by means of the air supply pipe 32^a. The 10 valve 33^a located in the cab 13 serves to establish communication between the reservoir 21 and the cylinder 30. The safety steps 34 which are pivoted to the floor of the car at opposite sides of the door 14 as at 35, 15 are connected by the links 36 to a common slide rod 37. A flexible connection in the nature of a cable or chain 38 trained over the guide pulleys 39 serves to connect the free extremity of the rod 37 with the free extremity of the latch arm 33 whereby the 20 steps 34 will be thrown to a bridging position upon releasing movement of the latch. A coiled compression spring 40 serves to normally throw the steps to inoperative position and said spring also functions to move 25 the latch 26 to locking position.

In order to provide a signaling means which will automatically inform the operator when the steps are unoccupied and clear 30 to permit the closing of the safety doors 14, the electric signaling means illustrated in Fig. 8 has been devised. The signaling means comprises a normally open circuit 41 which includes the source of current 42 a 35 signal 43 which is preferably arranged in the cab 13, and the contact members 44 and 45 disposed respectively on each step 34 and on the car floor directly therebeneath. The contact members of each step are arranged 40 in parallel in the circuit in such a manner that when either step is depressed the signal will be in operation. A short compression spring 46 is disposed between each step and the car floor to normally effect a sufficient 45 elevation of the step to dispose the contact members out of engagement. When either of the steps is occupied, the weight of the passenger will serve to depress the same sufficiently to engage the contact members 50 for closing the circuit, thereby advising the operator that it is unsafe to close the door. When all of the steps are clear the signal circuit is broken, thereby informing the operator that the doors may be closed with 55 safety.

The safety doors 14 are preferably provided with fenders 48 in the nature of bowed resilient leaf springs which normally tend toward relative separation from the side 60 faces of the door. The purpose of the fenders is to fend off passengers attempting to enter or leave the passages when the doors are in the act of closing. The fenders are designed to collapse against the side 65 faces of the door when the same is retracted

within the sides of the car for opening the passages. If desired a flexible covering 49 such as canvas or the like may be attached to the fenders 48 to obviate the possibility of the passengers clothing becoming caught 70 between the fenders and the door.

In addition to the safety doors 14, revolving doors or turnstiles 50 are provided and arranged within the car adjacent the 75 passages. The turnstiles 50 adjacent the entrance openings 11 operate to admit of the free entrance of passengers to the car but serve to prevent exit therefrom. The said means includes the ratchet wheel 51 mounted on the shaft 52 and the pawl 53 which co-acts 80 with the ratchet to limit rotation of said turnstiles in one direction. The obstructing fingers 54 prevent exit of the passengers from the entrance passages 11. Turnstiles 50 arranged adjacent the exit passages 12 85 are preferably housed by the vestibule wall 55 having a door-way 56 communicating therewith. These turnstiles are limited to rotation in one direction by means of the ratchet wheels and pawls 51 and 53 similar 90 to the ones heretofore described. In order to provide means to prevent the exit of the passengers through the passages 12 except upon the payment of the required fare, a coin actuated locking means is provided 95 which normally prevents rotation of the turnstiles. Said means includes a disk 58 mounted on the lower extremity of the turnstile shaft 52 and having cam surfaces 59 and notches 60 on the periphery thereof. 100 A detent 61 formed on the extremity of the pivoted detent arm 62 is normally disposed within one of the notches 60 to prevent rotation of the turnstile under the action of a tension spring 63. A solenoid 64 is operatively connected with the detent arm 62 and is adapted when energized to throw the detent arm to a position to release the detent from the notch 60. The solenoid is included 105 in a normally open circuit 65 having a source of supply 66 and spaced contact members 67 and 68 which are disposed at opposite sides of a coin chute 69. When the coin is deposited in the coin receiving opening 70 the same gravitates into engagement with and 110 bridges the contact members 67 and 68 to close the circuit 65. The closing of the circuit functions to energize the solenoid and release the detent from its notch, thereby 115 permitting the turnstile to be rotated. In 120 order to provide means for releasing the coin to allow the same to drop free of the contact members into the coin box 71, the contact member 68 is pivoted as at 72 and the lower extremity thereof is connected to 125 the throw rod 73, the free extremity of which is provided with a roller 74 arranged in the path of movement of the disk 58. As the turnstile revolves the cam surfaces 59 on the periphery of the disk co-act with the roller 130

74 to effect a movement of the throw rod 73, which in turn swings the contact member 68 to a position to release the coin. The spring 75 serves to return the contact member 68 to 5 a position for obstructing the passage of the next coin. A door 76 is provided adjacent the coin box 71 to permit of the removal of the coins therefrom at the end of each trip of the car.

10 In the exemplification of the invention which has been here illustrated, the safety doors 14 on the opposite sides of the car are respectively controlled independently but the controlling means for both sides are arranged in each cab 13 to permit the operator to open all of the safety doors on each side when arriving at an express station in which the platforms are disposed at either side of the car.

15 20 While the invention is set forth as a means for controlling or actuating car doors to permit of the entry and exit of passengers to and from the car, the system accomplished by said means is also considered a novel and 25 important feature of this invention. By this system the fares are collected and the entrance and exit of passengers to and from the car is efficiently controlled automatically after the operator of the car has effected the 30 opening of the safety doors.

While a single and preferred embodiment of the invention has been shown and described, no limitation is necessarily made thereto as the same is merely illustrative in 35 so far as it is covered by the appended claims.

Having thus described my invention, I claim as new and desire to secure by Letters Patent:—

40 1. In a car having entrance and exit passages, means permitting of free entry through the entrance passages and preventing exit therefrom, locking means for preventing free exit from the exit passages, 45 coin controlled means for releasing said locking means, outer safety doors for obstructing all the passages and manually controlled means for simultaneously effecting opening or closing of said doors.

50 2. In a car having entrance and exit passages, means permitting of free entry through the entrance passages and preventing exit therefrom, locking means for preventing free exit from the exit passages, 55 coin controlled means for releasing said locking means, outer safety doors for obstructing all the passages, manually controlled means for simultaneously effecting opening or closing of said doors, means for 60 retaining the safety doors respectively in their closed or opened position, and means for releasing said retaining means.

65 3. In a car having entrance and exit passages, means permitting of free entry through the entrance passages and prevent-

ing exit therefrom, locking means for preventing free exit therefrom, coin controlled means for releasing said locking means, outer safety doors for obstructing all the passages, manually controlled means for simultaneously effecting opening or closing of said doors, retaining means for locking the safety doors respectively in their opened position, means for releasing said retaining means, and means operable by said 70 releasing means for bridging the space between the car and an alighting platform.

4. In a car having entrance passages and exit passages, means for preventing exit from the entrance passages and means for 80 limiting the exit of the passengers from the exit passages comprising revolving doors in the exit passages, means for preventing the revolution of said doors in one direction, means for locking the revolution of said 85 doors in the opposite direction, and coin actuated controlling means for releasing said locking means.

5. The combination with a railway car having outer sliding doors and inner revoluble entrance and exit doors, of manually controlled means for simultaneously effecting the opening or closing of the sliding doors, means for locking the exit doors against the exit of passengers therefrom, 95 and coin actuated controlling means for releasing said locking means.

6. The combination with a railway car including entrance and exit passages of outer sliding doors and inner revoluble 100 doors for said passages, means for limiting the revolving doors to rotate in one direction, means for preventing exit from the entrance passages and coin actuated controlling means for the revolving doors of 105 the exit passages.

7. The combination with a railway car having outer sliding doors and inner revoluble entrance and exit doors, of manually controlled means for simultaneously 110 effecting opening or closing of the sliding doors, coin actuated controlling means for releasing the exit doors, means for retaining the sliding doors in open or closed position, means for releasing said retaining 115 means, and means for bridging the space between the car and an alighting platform, said bridging means being operable by said releasing means.

8. A railway car comprising entrance and 120 exit passages, automatic means operated to limit the use of said entrance passages as entrances, means for locking the exit passage against free exit therefrom, and coin actuated controlling means for releasing 125 said locking means to permit exit from the exit passage, in combination with outer safety doors adapted to close all of the passages.

9. A railway car comprising entrance and 130

exit passages, automatic means operating to limit the use of said entrance passage as an entrance, means for locking the exit passage against exit therefrom, coin actuated controlling means for releasing said locking means to permit exit from the exit passage, in combination with outer safety doors adapted to close all of the passages, and manually controlled means for simultaneously opening or closing said doors.

10. A railway car comprising entrance and exit passages, automatic means functioning to limit the use of said entrance

passage as an entrance, means for locking the exit passage against exit therefrom, coin 15 actuated controlling means for releasing said locking means to permit exit from the exit passage, in combination with outer safety doors adapted to close all of the passages, and manually controlled means for 20 simultaneously opening or closing said doors, said controlling means being arranged at a common controlling point in the car.

WALTER N. McCLELLAN.
